(57) **CLAIM**

The ornamental design for a paperclip lamp, as shown and described.

DESCRIPTION

FIG. 1 is a generally upper rear perspective view of a paperclip lamp according to the present invention, shown in the folded configuration;

FIG. 2 is a generally bottom rear perspective view of the paperclip lamp shown in FIG. 1;

FIG. 3 is a top plan view of the paperclip lamp shown in FIG. 1;

FIG. 4 is a bottom plan view of the paperclip lamp shown in FIG. 1;

FIG. 5 is a rear view of the paperclip lamp shown in FIG. 1;

FIG. 6 is a front view of the paperclip lamp shown in FIG. 1;

FIG. 7 is a right side view of the paperclip lamp shown in FIG. 1;

FIG. 8 is a left side view of the paperclip lamp shown in FIG. 1; and,

FIG. 9 is a generally upper rear perspective view of the paperclip lamp shown in FIG. 1, here shown in one extended position.
